UNITED STATES PATENT OFFICE.

SVEN JOSEF FREDRIK BERGENDAHL, OF GOTTFENBORG, SWEDEN.

MANIFOLD RECORDING BOOK OR PAD.

1,256,868.

Specification of Letters Patent. Patented Feb. 19, 1918.

Application filed January 6, 1917. Serial No. 140,898.

To all whom it may concern:

Be it known that I, SVEN JOSEF FREDRIK BERGENDAHL, a subject of the King of Sweden, residing at Gottenborg, in the county 5 of Gottenborg and Bohus and Kingdom of Sweden, have invented new and useful Improvements in Manifold Recording Books or Pads, of which the following is a specification.

10 This invention relates to manifold recording books or pads of the class wherein the single sheets, which are all joined together by means of a common stub are folded into a plurality of sections and the sections of 15 each single sheet spaced by means of carbon leaves, when said sheet is to be written upon, so that true copies can be recorded by merely writing on the uppermost section of the sheet.

20 It is known to provide such books, or pads with the carbons fitted to opposite edges of the sheets so that the carbons can be inserted alternately between each two sections of the folded sheet without being interfered with 25 when the folded sheet is removed. When using such books, however, as hitherto known, the carbon must be applied by hand and the sheet, which is to be written upon, must firstly be raised and the undermost 30 carbon applied above the innermost section of the sheet, whereupon the next section of the sheet is folded down above said carbon, and the next carbon applied upon the last mentioned section of the sheet, and finally 35 the outermost section of said sheet folded down above the just mentioned carbon—assuming the sheet to be triplicate folded. For any other number of folding sections the number of carbons and the manipulations when applying same will be in agreement therewith.

This invention has for its object to shorten the time required for performing the necessary operations and to provide a manifold 45 recording book or pad that will be particularly easy and convenient to use. My improved manifold book or pad can be constructed to suit duplicate, triplicate as well as quadruplicate sheets, and all these three 50 embodiments will be clearly explained below.

The above mentioned object of invention I obtain by means of stiffening members which act upon the carbons so that the car-

bon leaves will automatically position themselves in the proper places between the sections of the sheet when the sheet is raised and its folding sections sufficiently spaced. 55

In the accompanying drawings the above-mentioned three embodiments are illustrated 60 diagrammatically.

Figure 1 is a side elevation of a book with triplicate sheets with the uppermost sheet raised for the purpose of applying the carbons between its sections. 65

Fig. 2 is a plan view of the same book.

Fig. 3 is the same view as in Fig. 1 of a book with quadruplicate sheets.

Fig. 4 is a plan view of the last mentioned book. 70

Fig. 5 is a side elevation of a book with duplicate sheets with the uppermost sheet raised for applying the carbon and

Fig. 6 is a similar view of a book with triplicate sheets of a somewhat modified embodiment. 75

The same reference characters refer to similar parts throughout all the drawings.

Referring to the embodiment shown in Figs. 1 and 2, along one edge of a stiff base 80 1 of card board or similar material there are attached, by means of staples 3, the folded sheets 2 such, that they form a block and each of them can be expanded as shown since only one edge (the left-hand edge in 85 the drawing) is secured to the base 1. At the edge of the base 1, there is attached by means of the same staples 3 one edge of a carbon leaf 5, and at the opposite edge of the base 1 there is secured by means of 90 staples 4, the edge of another carbon leaf 6. The carbons 5 and 6 are attached to the block so that the carbon 5 can be inserted between the first and second sections 2^a and 2^b of the sheet, and the carbon 6 between 95 the second and third sections 2^b and 2^c of the same sheet. The sheet 2 is perforated or otherwise weakened adjacent the fixed (left-hand) edge so that, after writing on the uppermost sheet, this sheet can be easily detached and the next sheet exposed for writing. The carbon 5 along the two edges which are at right angles to the fixed edge, is provided with elastic stiffening members 7, such as strips of stiff card board, and the 100 opposite carbon 6 is provided in the same way with similar elastic stiffening members 8. 105

The improved pad works as follows. In starting, the carbon 5 lies above the uppermost sheet 2, and the carbon 6 above the first mentioned carbon. The uppermost sheet 2 is then grasped in the right hand corner 9 and pulled out, whereby the two carbons are caused to rise as illustrated in Fig. 1. As soon as the pull on the sheet 2 ceases, the carbon 5, under the influence of the stiffening members 7, descends above the inner or left-hand section 2^a, forcing this section downward, whereafter the carbon 6, by the influence of its elastic stiffening members 8 descends above the next or intermediate section 2^b, pushing down this section also, so that the outer or right-hand section 2^c comes down above the carbon 6. The carbons 5 and 6 will automatically regain the above mentioned starting positions as soon as the upper sheet 2 is detached from the pad and consequently, when raising the next sheet 2 (which after detachment of the first mentioned sheet constitutes the new uppermost sheet), the operation of the carbons will be as before.

In Figs. 3 and 4 a book, with quadruplicate folded sheets 2^a, 2^b, 2^c, and 2^d, is illustrated. The attaching of the sheets and of the two carbons 5 and 6 as well as the arranging of the elastic stiffening members 7 and 8 are the same as described in connection with the before-mentioned embodiment. The pad is here provided also with a third carbon 10, secured to the base 1 along the edge 11 of the base by means of staples 14, and this carbon is also provided with elastic stiffening members 13 which actuate it exactly as before mentioned regarding the elastic stiffening members 7 and 8. When grasping the uppermost sheet 2 in the lower right-hand corner 12, the sheet will be pulled out and thus all the three carbons moved upward into the positions illustrated in Fig. 3. As shown in Fig. 4 one stiffening member 7 of the carbon 5 is made rather wide so that, when the carbons stand in their raised position, the carbon 5 is supported against the edge of the third carbon 10 to prevent the carbon 5 from descending before carbon 10.

The carbon 10 moves into the space between the innermost or left hand section 2^a and the second section 2^b, the carbon 6 into the space between the second section 2^b and the third section 2^c, and the carbon 5 into space between the third section 2^c and the fourth or right hand section 2^d.

In Fig. 5 is shown a book having duplicate folded sheets in which both sections of the sheet 2 are attached to the base 1 as there is no need to raise more than one section for inserting of the carbon. Only one carbon is used, which is attached to the base 1 at the edge opposite to the edge where the sheet 2 is fastened, and is provided with elas-

tic stiffeners 8 as mentioned before. The working of this embodiment is similar to the before-mentioned embodiments.

Fig. 6 shows a modified form of book having triplicate folded sheets which might be termed a combination of the first and second described embodiments with the carbon 5 of the first mentioned embodiment substituted by the carbon 10 of the second embodiment.

If the pads are made of considerable thickness, that is, include so many sheets that the carbons would be too much worn through use, further carbons may be arranged in the same way as before mentioned within the book at suitable distances from the first mentioned carbons.

Having thus described and ascertained my said invention and how it is to be performed what I claim as new and want to protect by Letters Patent is:

1. In manifold recording books the combination of a base member, a plurality of sheets, bound together and to the base member along one edge, a carbon leaf also secured along one edge to said base member and elastic stiffening members attached to said carbon and rigidly attached to the base member so as to positively and automatically force the carbon leaf into position, as described.

2. A manifold recording book comprising a base member, a plurality of folded sheets bound together and to the base member along an edge parallel to the folding lines of the sheets, a carbon leaf secured at one edge to the said united edges, another carbon leaf secured at one edge to another edge of the base member, and elastic stiffening members attached to both carbons and rigidly attached to the base member so as to positively and automatically force the two carbons into position each between a pair of folding sections of the sheets, as described.

3. A manifold recording book comprising a base member, a plurality of folded sheets bound together and to the base member along an edge parallel to the folding lines of the sheets, a carbon leaf secured at one edge to the said united edges, another carbon leaf secured at its one edge to another edge of the base member, a third carbon leaf secured at one edge to a third edge of the base member and elastic stiffening members attached to each of the three carbons and rigidly attached to the base member so as to positively and automatically force the three carbons into position each between a pair of folding sections of the sheets, as described.

4. A manifold book comprising a base member, a plurality of folded sheets bound together and to the base member, a carbon leaf secured at one edge to the said united edges, another carbon leaf secured at one edge to another edge of the base member, a

third carbon leaf secured at one edge to a third edge of the base member and elastic stiffening members attached to each of the three carbons and rigidly attached to the 5 base member so as to positively and automatically force the three carbons into position each between a pair of folding sections of the sheets, the elastic stiffening members on one of the carbons being of sufficient 10 width to be supported against the edge of

the carbon which is secured on the adjacent edge of the base member when the carbons are raised, as described.

In testimony whereof I affix my signature in presence of two witnesses.

SVEN JOSEF FREDRIK BERGENDAHL.
